(57) **CLAIM**

The ornamental design for a watch, as shown and described.

DESCRIPTION

FIG. 1 is a front elevational view of a watch showing my new design;
FIG. 2 is a back elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a front, bottom, right side perspective view thereof;
and,
FIG. 8 is a back, top, left side perspective view thereof.
The broken lines depict portions of the watch that form no part of the claimed design.

1 Claim, 8 Drawing Sheets
